COUNTERBORE

Adam E. Sixer, Lakewood, Ohio

Application June 10, 1938, Serial No. 212,968

3 Claims. (Cl. 77—58)

This invention relates to adjustable counterbores, its object being to provide an improved tool of this kind adapted within a reasonable range of sizes to produce pilot and counterbore holes of any desired diameter and depth, thus dispensing with the relatively large number of solid, one-piece or non-adjustable counterbores heretofore required for the same range of sizes.

A further object is to provide an improved adjustable counterbore of the character described, said tool embodying the minimum number of parts, and all of the parts being of simple form, with the cutting parts easily replaceable or being capable of sharpening or renewal by simple operations.

A further object of the invention is to provide an adjustable counterbore which is readily adjustable and in which the cutting parts are rigidly held and are compelled to perform their proper duty with the assurance of accurate results.

Further objects are in part obvious and in part will appear more in detail hereinafter.

In the drawing, Fig. 1 represents a longitudinal sectional view on the line 1—1, Fig. 2, through a tool embodying the invention;

Fig. 2 is an end view, from the bottom in Fig. 1;

Fig. 3 is an end view from the top in Fig. 1;

Fig. 4 is a longitudinal sectional elevation, corresponding to Fig. 1, but on the line 4—4, Fig. 5, showing the same tool equipped with a pilot drill and bit of a different size;

Fig. 5 is an end view, from the bottom in Fig. 4;

Fig. 6 is a cross sectional view on the line 6—6, Fig. 4, looking in the direction of the arrows; and Fig. 7 is a diagram illustrating adjustment of the tool.

Counterbores of this class are used where it is desired to drill a hole of one diameter, the entrance to which is formed by a cylindrical recess or hole of larger diameter, such as a hole to receive the shank and head of a fastening bolt without any portion thereof extending above the surface of the piece. Usually the counterbore hole is approximately twice the diameter of the pilot hole, although the relations between the two may vary. According to present practice these counterbores are usually made in one piece or at least non-adjustable with pilot and bit portions mounted or held in fixed relation to each other so that a different tool is necessary for every size and for every combination of diameters of pilot and counterbore holes.

The present invention provides a counterbore which includes the necessary parts for supporting and holding rigidly in fixed relation to each other

a pilot drill and a cutting bit, the latter for producing the counterbore hole. The pilot drill may be of standard form and thus easily replaceable when dull or worn out. The bit may be an ordinary piece of rectangular tool steel, again of standard size, and adapted to be ground for the particular diameter of counterbore hole to be cut.

In the arrangement shown in the drawing, the tool comprises a main body portion 1 provided with a shank 2 adapted for connection to the driving spindle, the shank being usually tapered as shown. Said body portion is also provided with a recess or socket 3 coaxial with the axis of the shank 2 and adapted to receive the shank of 5 the pilot drill 4. The drill shank and the socket which receives it may also be tapered, as shown, the body portion being provided with the usual drift pin openings 5.

The lower portion of the body portion 1, while it contains the socket 3 coaxial with the axis of shank 2, nevertheless itself is eccentric to said axis, being bounded by surfaces of revolution about an axis offset with reference to the axis of shank 2 about which the tool as a whole revolves during the drilling operation. More particularly, 20 the body portion 1 is enlarged and offset to one side, as at 6, its lower or outer end having a cylindrical outer surface 7 extending between the end shoulder or abutment 8 and an intermediate shoulder or abutment 9, thus providing a sort of 25 head on the outer end of the body on which the bit carrier is mounted.

The bit carrier, indicated at 10, is a hollow cup-like member, symmetrical around the axis of the cylindrical head 7 and having a strong, thick end portion 11 and a sleeve 12 which extends beyond the shoulder 9 and is internally threaded to receive the threaded portion of a clamping member 13 having a hex head 14.

When the supporting member 10 has been 40 rotatably adjusted to bring the bit into close contacting relation with the pilot drill, it may be clamped in such position by screwing up the clamping member 14 by applying a wrench to the hex head thereof, another wrench being applied to the hex surfaces of the end member 11. 45 screwing up the members 10 and 13 causes them to clamp against the shoulders 8 and 9 and firmly fix the parts together. When fully adjusted and clamped member 13 may be further secured by 50 screwing up the set screws 15, as will be readily understood.

The hex shaped strong end portion 11 of the support 10 is provided with means for supporting the counterboring bit, such as a rectangular sock- 55

et or opening 16 in which the square shank of the bit 17 may be inserted, a set screw 18 being provided to hold it firmly in place. The protruding portion of the bit, indicated at 17a, Fig. 1, is ground off not only to provide the radially extending cutting edge 19, but to also provide the necessary clearance back of the cutting edge and at the periphery, as will be readily understood.

Figs. 1, 2 and 3 show the parts holding the maximum size of both pilot drill and bit. The pilot drill has its cutting portion extending through an opening 20 in member 11, somewhat larger than the drill itself. Also, the longitudinally extending corner edge of the bit 17, indicated at 21, Fig. 2, extends into the said opening 20 and hugs and lies alongside of the surface of the cutting portion of the pilot drill. Consequently with the parts in the positions shown in Figs. 1 and 2, the tool, when revolved about the axis 20 of the shank 2, will cut a pilot hole followed by a counterbore hole of approximately twice its size.

Figs. 4 and 5 illustrate the tool fitted to produce smaller pilot and counterbore holes and specifically such holes are half the diameter of the tool before described. The drill, 4a in this case, has the same size shank, but its cutting end portion 4b is of half the size. The bit 17b has the same size shank where it enters the recess 16, but its protruding end portion has been ground off to form a smaller cutting end portion 17c. Also, it will be understood that in Fig. 5, after inserting the proper sizes of pilot drill and bit, the member 10 has been adjusted around its own axis in the counterclockwise direction, Fig. 5, to again bring the longitudinally extending edge 21 of the bit into close neighboring and contacting relation with the pilot drill.

Fig. 7 is a diagram illustrating adjustment of the tool for three different sizes of drill and bit, large, intermediate and small. In each case, the length of the substantially radial cutting edge of the bit, marked 19, is equal to one half the diameter of the pilot drill. The large, intermediate and small bits are respectively indicated at a, b and c, and the large, intermediate and

small pilot drills at a₁, b₁ and c₁. Adjustment of the bit carrier 10 is about the axis indicated at X, while the tool as a whole, during the cutting operation, rotates about the axis Y.

The tool as a whole is of simple form and is capable of being set or adapted for any size of hole within a reasonable range. By selecting cutting bits of the proper length or adjusting them longitudinally of the axis, the end cutting edge of the bit may be brought nearer to or farther from the end of the pilot drill. In all cases the bit cuts right up close to the boundary of the previously cut pilot hole and a clean, true job is completed. Both the drill and the bit are readily replaceable when dull or worn.

What I claim is:

1. A counterbore comprising a holder having a shank for attachment to a spindle, said holder having a socket axially aligned with said shank for receiving a drill, said holder having an outer cylindrical surface eccentric to said drill socket, a cup-shaped carrier having a sleeve portion rotatable about said cylindrical surface and having an end portion, there being an opening through said end portion through which said drill passes, there being means for mounting a cutting bit on said carrier to one side of said opening, and means for clamping said carrier in adjusted positions on said holder, the relation between the parts being such that said bit is adjustable in such a manner that it may have its cutting edge moved substantially into contact with said drill.

2. A counterbore as in claim 1 wherein said mounting means is arranged to hold said bit in various adjusted positions longitudinally of said drill.

3. A counterbore, comprising a holder having a socket for receiving a pilot drill, a carrier mounted upon said holder, means for mounting a counterboring bit on said carrier wholly to one side of said drill, and said carrier being adjustable on said holder to move said bit in an arc which intercepts a drill in said socket, whereby said bit may be moved substantially into contact with varying size drills in said socket.
